WEFT FEEDERS FOR WEAVING LOOMS

Raymond Dewas, Amiens, France

Application February 20, 1956, Serial No. 566,655

Claims priority, application France February 24, 1955

8 Claims. (Cl. 139—123)

This invention relates to improvements in weft feeders for weaving looms in which the weft is fed continuously from large fixed bobbins, has reference to the heads arranged on the ends of the needles or bands of the kind described in the complete specification of my earlier U.S. Patent No. 2,192,728 and has for its general object to improve the elastic thread clamp on the head of the conveying needle.

In particular the invention refers to one of the variants described in the said complete specification, namely that in which the part of the thread clamp coming into contact with the side of the head of the conveying needle comprises a shoe-like element simply held in place by the free end of the blade spring being elastically pressed against the said surface.

It has been found that such an arrangement may present certain inconvenience because the force of the blade spring on the shoe-like element does not operate with sufficient precision and accuracy and such force may even change in the course of operation.

With the particular view of affecting the application of the force of the blade spring with precision and accuracy and further to enable the position of the point of application of this force to be regulated properly, the invention has the further objects of introducing the following principal improvements.

Firstly, the shoe-like element of the thread clamp is located in operative position at two points at one of which the force of the blade spring is applied directly or indirectly to the shoe-like element whilst at the other the shoe-like element is held so as to allow the element to tilt.

Secondly, in one arrangement described hereinafter the shoe-like element is provided with a rearwardly extending prolongation that is fixed, with a certain degree of freedom of movement, either on one side of the head of the conveying needle or on the blade spring.

Thirdly, the indirect application of the force of the blade spring on to the shoe-like element is effected by interposing an intermediary part between the blade spring and the shoe so as to ensure a correct transmission of the pressure from the blade spring to the shoe in all relative positions of these parts.

Fourthly, the intermediary part preferably is constituted by a ball.

Fifthly, the front part of the blade spring is provided with a plurality of recesses adapted to receive the ball constituting the intermediary part so as to enable the ball to be placed in any one of the recesses more or less distant from the end.

Sixthly, the other part, preferably the shoe-like element, is provided with a groove suitably profiled to receive the ball that constitutes the intermediary part between the shoe and its associated blade spring and

Seventhly, the middle part of the blade spring is narrow to facilitate its lateral movement under the action of the thread.

These characteristics, as well as others which will appear hereinafter, are fully disclosed in the following de-

2

scription of the non limitative forms of construction given by way of simple examples and shown in the dia-grammatic figures of the drawing attached to this complete specification, in which:

5 Figure 1 is a plan view of the head of a conveying needle with one form of thread clamp, according to this invention, applied thereto;

Figure 2 is a longitudinal vertical section taken on the line II—II of Figure 1;

10 Figure 3 is a plan view of the blade spring of the thread clamp;

Figure 4 is a fragmentary detail view in vertical section taken on the line IV—IV of Figure 3;

15 Figure 5 is a plan view of the shoe-like element of the thread clamp;

Figure 6 is a vertical longitudinal section through the thread clamp taken on line VI—VI of Figure 5;

20 Figure 7 is a vertical transverse section, on a larger scale, through the thread clamp taken on the line VII—VII of Figure 5;

Figure 8 is a plan view of a modified form of thread clamp according to this invention;

Figure 9 is a vertical longitudinal section through Figure 8 taken on the line IX—IX of that figure;

25 Figure 10 is a plan view of the shoe-like element;

Figure 11 is a vertical longitudinal section through Figure 10 taken on the line XI—XI of that figure; and

30 Figure 12 shows a vertical transverse section through Figure 10 taken on the line XII—XII of that figure and drawn to a larger scale.

In these figures 1 is the conveying needle of which the side 1a faces the reed on the batten and the side 1b faces the cloth, 2 is the point of support for the thread and 4 is the cutting blade.

35 The thread clamp, arranged to hold the thread 3 during its passage into the head of the conveying needle, is constituted by the co-operation of the wall 1c of the needle with the shoe 5, being pressed there against by the blade spring 6 mounted on the wall 1c by means of 40 the screws 7 and 7'. This arrangement enables the pressure exerted by the blade spring 6 to be regulated by adjustment of the screw 7' whose head is in contact with the outer surface of the blade spring.

The front end of the blade spring 6 is provided with 45 several recesses 8, the three shown in the drawings, each being adapted to accommodate the ball 9 which constitutes an intermediary part transmitting the force of the pressure exercised by the blade spring to the shoe-like element 5.

50 The shoe-like element 5 has the longitudinal groove 10 of suitable profile (that may be of V-shape as shown or perhaps of U-shape with rounded or flat bottom) to co-operate with the ball 9.

The ball 9 which may be of steel, industrial stone, 55 agate or other suitable pressure transmitting material, has the advantage of always correctly transmitting the pressure from the blade spring to the shoe-like element regardless of the relative positions of these parts.

The three recesses 8 are made by countersinking holes 60 so spaced that the countersinks overlap to such extent as to enable the ball 9 to be easily shifted from one to another so that the force of the pressure of the spring can be applied precisely at the point necessitated by the nature of the thread, its thickness and so on.

65 The shoe-like element 5 has a rearwardly extending prolongation 5a terminating in a stub 5b which cannot come into contact with the wall 1c unless the thread is engaged by the thread clamp.

The stub 5b is loosely fitted on the stud 11 the stem 70 of which is mounted in the wall 1c. In this way the stud 11 and the ball 9 constitute two points of support that assure the position of the shoe-like element. In

use when the thread engaged by the thread clamp, the pivoting of the shoe-like element takes place around the stub 5b.

If the blade spring 6 is, as shown, narrow at its middle part, the shoe-like element, when actuated by the thread, can move laterally, by rotation about the stud 11, with sufficient amplitude, which although small, facilitates the discharge of impurities.

The fact that the stud 11, around which the shoe-like element 5 pivots when the thread enters the thread clamp, is located at a distance from the zone of clipping, has the advantage that the shoe-like element, when rising, assumes only a small inclination and that its rear end *a* is raised so that impurities are easily discharged to the rear which is of advantage, inter alia, when handling a fluffy thread or a thread having mites.

The modified construction shown in Figures 8 to 12 differs from that already described by the fact that the shoe-like element 5 has no rearwardly extending prolongation and that, instead of being mounted on the wall 1c, it is attached loosely to the blade spring by the stud 12 which passes freely through the rear part so as to allow it to rise under the action of the thread. In this construction the two points of support are constituted respectively by the ball 9 and the stud 12.

It is to be understood that without exceeding the scope of the invention, variants and improvements in detail can be conceived.

For instance, the fixing of the rearwardly extending prolongation 5a of the shoe-like element 5 in the construction shown in Figures 1 to 7 can be effected on the blade spring 6 instead of being on the wall 1c.

By way of further example, the stud 11 could be integral with the stub 5b and pass through a hole in the wall 1c.

Alternatively the rear part of the shoe-like element may be rounded to allow, when the weft feeder returns to its position outside the fabric, of the insertion of a cleaning sheet mounted, for example, inside the head of the conveying needle, behind the shoe-like element on the end of a rod co-operating with a stationary abutment for moving the sheet into the thread clamp and with an elastic arrangement for bringing the sheet back to its rest position.

What I claim is:

1. A thread clamp for the conveying needle of a weaving loom with a stationary weft supply bobbin, having, in combination, a cantilever blade spring anchored at one end thereof on the body of the conveying needle, an elongated shoe-like element having a portion thereof adapted to bear flat against a part of the conveying needle, said shoe-like element being shorter than said blade spring and being tiltably maintained at two points thereof longitudinally spaced apart, namely, at a first point by the free end of the blade spring which urges said element against the needle body, and at a second point located between said first point and the point where said blade spring is anchored on the needle body, whereby said shoe-like element is capable of orienting itself independently of said blade spring in any direction and to bear flat over its entire contact area against said needle part.

2. A thread clamp according to claim 1, further comprising means for adjusting the position of said first maintaining point longitudinally of said blade spring and shoe-like element.

3. A thread clamp according to claim 1, further comprising means for adjusting the position of said first maintaining point longitudinally of said blade spring and shoe-like element, said first point adjusting means comprising a plurality of recesses in one of the two facing surfaces of the free end of the blade spring and shoe-like element, a longitudinal groove in the other of said two surfaces, and a ball housed selectively in one of said recesses and in said groove.

4. A thread clamp for the conveying needle of a weaving loom with a stationary weft supply bobbin, having, in combination, a cantilever blade spring anchored at one end thereof on the body of the conveying needle, an elongated shoe-like element having a portion thereof adapted to bear flat against a part of the conveying needle, said shoe-like element being shorter than said blade spring and being tiltably maintained at two points thereof longitudinally spaced apart, namely, at a first point by the free end of the blade spring which urges said element against the needle body, and at a second point by a stud located on said needle body between said first point and the point where said blade spring is anchored on the needle body, whereby said shoe-like element is capable of orienting itself independently of said blade spring in any direction and to bear flat over its whole area against said needle part.

5. A thread clamp for the conveying needle of a weaving loom with a stationary weft feeding bobbin having, in combination, a cantilever blade spring adjustably anchored at one end thereof on the body of the conveying needle, an elongated shoe-like element having a portion thereof adapted to bear flat against a part of the conveying needle, said shoe-like element being tiltably maintained at two points thereof longitudinally spaced apart on said clamp so that said shoe-like element is capable of orienting itself in any direction and to bear flat over its whole contact area against said needle part, a rearwardly projecting prolongation on said element, a stud on the blade spring tiltably co-operating with the rear end of said prolongation and means for transmitting the force of the pressure of the blade spring to the shoe-like element to said element against said conveying needle.

6. A thread clamp for the conveying needle of a weaving loom with a stationary weft feeding bobbin having, in combination, a cantilever blade spring adjustably anchored at one end thereof on the body of the conveying needle, an elongated shoe-like element having a portion thereof adapted to bear flat against a part of the conveying needle under the action of said blade spring, said shoe-like element being tiltably maintained at two points thereof longitudinally spaced apart on said clamp so that said shoe-like element is capable of orienting itself in any direction and to bear flat over its whole contact area against said needle part, a plurality of recesses in the free end of the blade spring facing the shoe-like element, a longitudinal groove in the said element facing the blade spring and a ball housed in one of the said recesses and in the said groove, said ball constituting one of said two longitudinally spaced points at which said shoe-like element is maintained.

7. A thread clamp for the conveying needle of a weaving loom with a stationary weft feeding bobbin having, in combination, a cantilever blade spring adjustably anchored at one end thereof on the body of the conveying needle, an elongated shoe-like element having a portion thereof adapted to bear flat against a part of the conveying needle under the action of said blade spring, said shoe-like element being tiltably maintained at two points thereof longitudinally spaced apart on said clamp so that said shoe-like element is capable of orienting itself in any direction and to bear flat over its whole contact area against said needle part, a rearwardly projecting prolongation on such element, a stud on the conveying needle tiltably co-operating with the rear end of said prolongation, a plurality of recesses in the free end of the blade spring facing the shoe-like element, a longitudinal groove in the said element facing the blade spring and a ball housed in one of the recesses and in the said groove, said ball and said stud respectively constituting said two longitudinally spaced points at which said shoe-like element is maintained.

8. A thread clamp for the conveying needle of a weaving loom with a stationary weft feeding bobbin

having, in combination, a cantilever blade spring adjustably anchored at one end thereof on the body of the conveying needle, an elongated shoe-like element having a portion thereof adapted to bear flat against a part of the conveying needle under the action of said blade spring, said shoe-like element being tiltably maintained at two points thereof longitudinally spaced apart on said clamp so that said shoe-like element is capable of orienting itself in any direction and to bear flat over its whole contact area against said needle part, a rearwardly projecting prolongation on said element, a stud on the blade spring tiltably co-operating with the rear end of said prolongation, a plurality of recesses in the free end

of the blade spring facing the shoe-like element, a longitudinal groove in the said element facing the blade spring and a ball housed in one of the said recesses and in the said groove said ball and said stud respectively constituting said two longitudinally spaced points at which said shoe-like element is maintained.
